COMBINED HOOD AND GRILLE FOR A TRACTOR OR THE LIKE

Henry Dreyfuss, South Pasadena, William F. H. Purcell, Pasadena, and James M. Conner, Glendale, Calif., assignors to Deere & Company, Moline, Ill., a corporation of Delaware

Filed Oct. 23, 1961, Ser. No. 67,247

Term of patent 14 years

(Cl. D14—3)

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a side elevational view of a combined hood and grille for a tractor or the like, showing our new design.

FIG. 2 is a top plan view thereof.

FIG. 3 is a side elevation thereof as seen from the side opposite that of FIG. 1.

FIG. 4 is a perspective view thereof as seen from the right front.

FIG. 5 is a perspective view thereof as seen from the left front.

FIG. 6 is a perspective view thereof as seen from the top and front.

FIG. 7 is a side elevational view of a modified form of combined hood and grille for a tractor or the like, shown in FIG. 1.

FIG. 8 is a top plan view thereof.

FIG. 9 is a side elevation thereof as seen from the side opposite that of FIG. 7.

FIG. 10 is a perspective view thereof as seen from the right front.

FIG. 11 is a perspective view thereof as seen from the left front.

FIG. 12 is a perspective view thereof as seen from the top and front.

This application is a continuation-in part of our co-pending applications Ser. No. D. 62,782 and Ser. No. D. 63,094, both filed November 9, 1960, now abandoned.

We claim:

The ornamental design for a combined hood and grille for a tractor or the like, substantially as shown and described.
